UNITED STATES PATENT OFFICE.

JOHN A. WALDBURGER, OF MCKEESPORT, PENNSYLVANIA, ASSIGNOR TO FORTER MILLER ENGINEERING COMPANY, OF PITTSBURG, PENNSYLVANIA, A CORPORATION OF PENNSYLVANIA.

FURNACE.

No. 880,840.

Specification of Letters Patent.

Patented March 3, 1908.

Application filed February 19, 1907. Serial No. 358,184.

To all whom it may concern:

Be it known that I, JOHN A. WALDBURGER, a citizen of the United States, residing at McKeesport, in the county of Allegheny and State of Pennsylvania, have invented certain new and useful Improvements in Furnaces, of which the following is a specification, reference being had therein to the accompanying drawing.

10 My invention refers to the improvements in furnaces, more particularly heating furnaces for billets, blooms and other articles and it has for its object to provide a construction whereby the gases of combustion will circulate below the articles to be heated as well as above. The construction whereby this object is secured is shown in the accompanying drawings, wherein,

Figure 1 is a view in front elevation partly in section, the sectional portions being indicated by the line I—I of Fig. 2. Fig. 2 is a partial longitudinal vertical section indicated by the line II—II of Fig. 1. Figs. 3 and 4 are vertical cross sectional views on an enlarged scale indicated by the lines III—III and IV—IV respectively of Fig. 6. Fig. 5 is a horizontal sectional view on two planes, indicated by the section line V—V of Fig. 4. Fig. 6 is a longitudinal vertical sectional view similar to Fig. 2 showing a modified construction providing for circulation of the heated air and gas. Fig. 7 is a vertical sectional view on the line VII—VII of Fig. 6.

The furnace is generally constructed similar to heating furnaces for the same purpose, being provided with the usual side walls 2, 2, longitudinally arranged supporting ridges, benches or piers 3 having intervening spaces 4 for reception of the slag which ordinarily falls down upon the floor of the furnace, and is closed at the ends by walls 5, 5, and covered by the usual arched roof 6. The roof as shown is constructed by double arched layers having an intervening longitudinally extending air space 7, through which the air circulates and becomes heated in its progress toward the front end of the furnace, becoming mixed with the gas for combustion.

8 is the main gas supply pipe from which by valve-controlled passages 9 the gas circulates to the interior of the furnace, the gases of combustion passing backwardly above the benches as indicated by the arrows 'a' and finally outward to the stack

through tunnel 10 or any other suitable conductor. At each side of the furnace, extending downwardly through the walls, are located supplemental gas supply ports 11, communicating by pipes 9' with the main pipe 8, as clearly shown in Fig. 1, while similar air supply ports 12 opening to the atmosphere lead downwardly through the walls adjacent to ports 11, the gas ports and air ports communicating with independent cross ports 13, 14, respectively extending transversely of the furnace as shown. By this construction air and gas are introduced into the lower front portion of the furnace, becoming heated in their passage through the walls, and the air and gas commingle by means of communicating ports leading upwardly from ports 13 and 14 and emerge by a common port 15 into the lower front portion of the furnace, below the ingots, etc. lying upon benches 3. Such gas and air in combustion circulate backwardly underneath the objects to be heated, as indicated by the arrows 'b', finally escaping to the stack through conduit 10. The floor of the furnace between the benches 3, for a considerable portion of its length, is sloped downwardly toward one end as indicated at 16 Figs. 2 and 6, such sloping bottom portions leading into a cross channel or gutter 17 opening outwardly at one or both sides of the furnace. By this construction the slag at the hottest end of the furnace will flow down along the floor and outwardly, thereby preventing an accumulation of slag or other refuse, and facilitating the free circulation of the gases. The under circulation, as thus provided for, constitutes the important feature of my invention, giving a thorough, even heating action upon all portions of the articles being treated, and is secured by means of the lower distributing ports for the gas and air. It will be understood that the gas supply passages as well as the air supply passages are controlled by suitable dampers or valves, whereby the amount of each may be suitably regulated to suit the requirements as will be readily understood.

In Fig. 2 I have shown a construction whereby the heated incoming air passing through channel 7 is deflected upwardly by means of a conduit 18 into an air box 19 located above the furnace, and provided with supply conduits 20 leading downwardly

into the upper front interior of the furnace at the point of combustion, immediately above and in front of the gas supply ports. By this construction I secure a more thorough commingling of the air and gas by directing the flow of the air, and also provide means by which the previously highly heated air coming through the double arched roof may be partially utilized after mixture with the 10 gas for the under supply.

As shown in Figs. 1 and 2, the gas is conducted as described to the lower port 13 by ports 11 and pipes 9', while conductors 21 at one or both sides communicate with the air 15 port 14 so that the heated air combining with the gas from port 13 will thus reach the point of combustion underneath the ingots in a highly heated condition. The circulation of the gas otherwise is however the same 20 as has already been described.

The operation of the invention will be readily understood from the foregoing description.

The articles to be treated are preferably 25 introduced from the back end and caused to travel through the furnace toward the combustion end thereof, being introduced and taken away through suitable door-covered openings 22 and 23 in the usual way. The 30 heating operation is rendered more even and rapid by reason of the combustion of the gas both above and below and necessarily around the ingots at all sides, and results in a greater output and more successful operation of the 35 furnace.

The invention may be changed or varied in different features or details of construction, or its novel features may be applied to furnaces of other or different types, but all 40 such changes are to be considered as within the scope of the following claims.

What I claim is:

1. A heating furnace provided with longitudinally arranged supporting benches having vertically arranged side walls and intervening spaces downwardly sloping floors, and transverse air and gas ports each communicating with ports opening into said spaces below the top of said benches at the 50 lower end of said sloping floors, substantially as set forth.

2. A heating furnace provided with longitudinally arranged supporting benches having vertically arranged side walls and intervening spaces, downwardly sloping floors, a transverse gutter arranged to receive the slag from said floors and carry it off to the outside of the furnace, and transverse air and gas ports each communicating with ports opening 55 into said spaces below the top of said benches at the lower end of said sloping floors, substantially as set forth.

3. A heating furnace provided with supporting benches and intervening spaces, and 60 transverse air and gas ports each communica-

cating with ports opening into said spaces below the supporting level of said benches, substantially as set forth.

4. A heating furnace provided with supporting benches and intervening spaces, and 70 transverse air and gas ports each communicating with ports opening into said spaces below the supporting level of said benches, with additional means for supplying fuel in combustion above the supporting surface of 75 said benches, substantially as set forth.

5. A heating furnace provided with supporting benches and intervening spaces, and a transverse fuel supply port communicating through the wall of the furnace with a fuel 80 supply conduit and opening into the lower front portion of said intervening spaces below the supporting level of said benches, substantially as set forth.

6. In a heating furnace, the combination 85 with the inclosing walls and longitudinally arranged supporting benches separated by intervening spaces, of transversely arranged air and gas supply ports located in front of and below the level of the supporting walls 90 and having ports leading upwardly and bodily through the brickwork to deliver fuel to the spaces between and below the upper surface of the supporting benches, substantially as set forth. 95

7. In a heating furnace, the combination with the inclosing walls and longitudinally arranged supporting benches separated by intervening spaces, of transversely arranged air and gas supply ports located in front of 100 and below the level of the supporting walls and having ports leading upwardly and bodily through the brickwork to deliver fuel to the spaces between and below the upper surface of the supporting walls, and means for 105 supplying fuel in combustion above said benches, substantially as set forth.

8. In a heating furnace, the combination with a series of supporting benches separated by intervening spaces, of inclosing walls, 110 lower transverse air and gas ports communicating with ports opening below the tops of said benches, and means for heating and supplying air and gas to said ports, substantially as set forth. 115

9. In a heating furnace, the combination with a series of supporting benches separated by intervening spaces, of an inclosing structure provided with lower transverse air and gas ports communicating with ports opening 120 into the front lower portion of the furnace interior and embodying preliminary heating ports leading to said transverse ports, and means for supplying gas through some of said preliminary heating ports to said gas port, 125 substantially as set forth.

10. In a heating furnace, the combination with a series of supporting benches separated by intervening spaces, of inclosing walls and foundation brickwork provided with trans- 130

verse air and gas ports communicating with sloping ports opening into the intervening spaces below the tops of said benches, means for preliminarily heating and supplying air and gas to said transverse ports, and means for supplying air and gas to the upper interior of the furnace, substantially as set forth.

11. In a heating furnace, the combination with a series of supporting benches separated by intervening spaces, inclosing walls provided with circulation ports, and a roof having an air heating passage; of lower transverse air and gas ports, means for supplying

gas to said lower gas port and also to the upper interior of the furnace, and a hot air 15 conductor communicating with the air heating passage of the roof, with said lower transverse air passage, and with the upper interior of the furnace respectively, substantially as set forth.

In testimony whereof I affix my signature in presence of two witnesses.

JOHN A. WALDBURGER.
